UNITED STATES PATENT OFFICE.

TERENCE F. CURLEY, OF BROOKLYN, NEW YORK.

DESIGN FOR A DISPLAY-BOX.

SPECIFICATION forming part of Design No. 35,285, dated November 12, 1901.

Application filed October 11, 1901. Serial No. 78,390. Term of patent 14 years.

To all whom it may concern:

Be it known that I, TERENCE F. CURLEY, a citizen of the United States, and a resident of the city of New York, borough of Brooklyn, in the county of Kings and State of New York, have invented and produced a new and original Design for a Display-Box, of which the following is a specification, reference being had to the accompanying drawings, forming part thereof, in which—

Figure 1 is a perspective view of a display-box, showing my design. Fig. 2 is a rear end elevation of the same, and Fig. 3 is a transverse section of the same.

The invention relates to boxes for displaying and containing cutlery, such as pocket-knives and the like.

The design in its entirety consists of a box A, open at the rear end and having its sides B formed with triangular legs extending below the bottom of the box to incline the box,

as shown in Figs. 1 and 3, the top C of the box being concaved and the front D extended upward beyond the concave portion of the top, as plainly indicated in Fig. 3. 25

The essential feature of the design consists in the inclined box open at the rear end and appearing with a concave top and an extended front.

Having described my invention, what I claim as new, and desire to secure by Letters Patent, is—

The design for the display-box herein shown and described.

In testimony whereof I have signed my name to this specification in the presence of two subscribing witnesses.

TERENCE F. CURLEY.
